United States Patent Office

Des. 223,631
Patented May 16, 1972

223,631

AIRCRAFT NAVIGATION LIGHT INDICATOR

Lloyd W. Spiro, 20510 Napa St.,
Los Angeles, Calif. 91306

Filed Sept. 23, 1970, Ser. No. 25,167

Term of patent 14 years

Int. Cl. D26—06
U.S. Cl. D48—32

FIG. 1 is a perspective view of the aircraft navigation light indicator showing my new design;

FIG. 2 is a side elevational view thereof; and

FIG. 3 is an end view thereof.

I claim:

The ornamental design for an aircraft navigation light indicator, substantially as shown.
